UNITED STATES PATENT OFFICE.

LOUIS J. WITHMAN, OF PLAINVILLE, MASSACHUSETTS.

DESIGN FOR JEWELRY-STOCK.

SPECIFICATION forming part of Design No. 16,814, dated July 20, 1886.

Application filed March 6, 1886. Serial No. 191,351. Term of patent 34 years.

To all whom it may concern:

Be it known that I, LOUIS J. WITHMAN, a citizen of the United States, residing at Plainville, county of Norfolk, and State of Massachusetts, have invented and produced a new and original Design for Stock for Jewelry, of which the following is a specification, reference being had to the accompanying drawing, forming part thereof.

My design relates to stock such as is employed in manufacturing articles of jewelry; and it consists of a piece of stock which represents a series of vertical and horizontal bars simulating woven splint basket-work, one series of which represents rope.

The drawing shows a face view of my design for jewelry-stock in the form of a brooch.

A brooch constructed in accordance with this illustration of my design will have, as shown, horizontal members a, which are made to represent rope, and plain vertical members b, the members a and b representing woven splints, such as commonly employed in basket-work, and provided with a surrounding border, A.

Before my design it has been customary to simulate braided, reticulated, woven, and other ware for use in jewelry, and articles of jewelry have been made in the shape of a basket. My design does not extend thus far nor comprehend such structures, but consists solely in jewelry-stock having the appearance of basket ware or work, as shown.

What I claim is—

The design for jewelry-stock comprehending the representation of basket work or ware of horizontal and vertical interwoven strands or splints, one series of which resembles rope, substantially as shown and described.

In testimony whereof I have signed my name to this specification in the presence of two subscribing witnesses.

LOUIS J. WITHMAN.
